UNITED STATES PATENT OFFICE.

EDWARD T. BREEN, OF NEW HAVEN, CONNECTICUT.

CHAIR SEAT.

Application filed February 2, 1925. Serial No. 6,312.

To all whom it may concern:

Be it known that I, EDWARD T. BREEN, a citizen of the United States, residing at New Haven, in the county of New Haven and State of Connecticut, have invented certain new and useful Improvements in Chair Seats, of which the following is a specification, reference being had therein to the accompanying drawings.

10 This invention relates to a new and improved chair seat for a folding chair or the like.

15 Among the aims and objects of the invention may be recited the provision of a device of the character mentioned, which shall be of simple design, that may be readily applied to a folding chair of the conventional type or in substitution of a worn seat or one to be removed for other reasons, 20 wherein the seat portion will be rigidly supported at its edges, capable of sustaining the maximum weight, and composed of few parts that combine to form a rigid structure that may be produced at the minimum cost.

25 The improvements in the details and arrangement of parts will be apparent from an inspection of the accompanying drawings, in connection with the description hereinafter contained, and wherein a preferred embodiment of the invention is disclosed for the purpose of imparting an understanding of the same.

30 Referring to the drawings, in which like numerals of reference designate like parts in the several figures:

Figure 1 is a perspective view of a folding chair having my improved chair seat connected therewith;

40 Figure 2 is a rear view thereof;

Figure 3 is a side elevation thereof when partially folded;

Figure 4 is an enlarged plan view of my improved chair seat;

45 Figure 5 is a side elevation thereof; and

Figure 6 is an enlarged sectional view thereof taken generally upon line 6—6 of Figure 4.

50 In the drawings, 10 and 11 are the front and rear legs respectively of a folding chair; 12 is the back bar, forming part of the chair back 14, that extends between the upper ends of the front legs 10 and connected therewith by a rod 13. These parts are old and well known in the art and constitute no part of my present invention.

55 My improved chair seat comprises a rod

15 that is bent near its outer ends at 16, so as to pass around and under the upper end of the front legs 10 and coiled at its outer ends to form the loops 17, through which 60 is projected the rod 13, whereby a pivotal connection is formed with the chair.

The frame 18 of the chair seat is constructed preferably of a single rod having two substantially parallel side portions that 65 terminate at their outer free ends in the loops 19, which encircle the rod 15 and provide a support at one end for the chair seat. These side portions are joined by the front bar 20, which is in a lower plane than the 70 parallel side portions and connected therewith through the curved portions 21, spaced apart a less distance than the parallel side portions, substantially as shown in Figure 4. These curved portions are of such size as 75 to encircle and form a pocket for the rung 22 connecting the upper ends of the rear legs 11, in which it is seated when the chair is in its open position.

Secured to the frame 18 is the seat portion 23, which may be of leather, carpet, or other material, as may be desired, with the end 24 projecting in rear of the rod 15, which extends through a pocket 25 therein.

In practice my improved chair seat is assembled with the chair substantially as shown in Figures 1, 2 and 3, by passing the rod 18 through the loops 17, and back bar 12.

When the chair is open, the rung 22 is projected into the curved portions 21 of the frame and thus locks the chair parts against accidental closing or collapse. Irrespective of the weight that may be placed upon the chair, the seat will not collapse or break 95 as with a chair having the ordinary carpet seat, as the same is supported upon all sides by a metal frame.

There are minor changes and alterations that may be made within my invention, and I would therefore have it understood that I do not limit myself to the exact construction herein shown and described, but claim all that falls fairly within the spirit and scope of the appended claims.

100 Having described my invention, what I claim as new and desire to secure by Letters Patent, is:—

1. In a folding chair, a frame having sides and having a front rung, a seat frame having a front part removably engaged with the rung and having sides formed with

eyes at their rear ends, a rod extended through the eyes and having its end portions extended rearwardly at approximately right angles and disposed on the inner faces 5 of the chair frame sides and then being extended outwardly and upwardly, and formed with eyes which are disposed on the outer faces of said chair frame sides, and a second rod extended through each of the 10 said last named eyes and through each of the chair frame sides.

2. In a chair, a main frame having sides and having a front rung, a seat frame having a front part removably engaged with 15 the front rung, and having sides formed with eyes, a rod extended through said eyes and having its end portions disposed on opposite faces of the respective frame sides and means to pivotally connect the extremi-

ties of said end portions of the rod to the 20 frame sides.

3. In a folding chair, a main frame having sides and having a front rung, a wire seat frame having an intermediate part 25 thereof formed into hook shape to removably engage over and around said front rung and having its end portions formed to provide sides for the seat frame, said end portions terminating in eyes, a rod forming the rear of the seat frame and passed 30 through said eyes, and means to pivotally connect said rod to the sides of the main frame, so as to pivotally support the rear end of the seat frame from the main frame.

In testimony whereof, I have hereunto 35 affixed my signature.

EDWARD T. BREEN.
